Primary Examiner — Richard Kearney

(57) **CLAIM**

The ornamental design for a rear combination lamp for automobiles, as shown and described.

DESCRIPTION

1. Rear combination lamp for automobiles

1.1 : Perspective

1.2 : Front

1.3 : Back

1.4 : Left

1.5 : Right

1.6 : Top

1.7 : Bottom

1.1 is a perspective view of a Rear combination lamp for automobiles showing our new design; 1.2 is a front elevation view thereof; 1.3 is a rear elevation view thereof; 1.4 is a left side elevation view thereof; 1.5 is a right side elevation view thereof; 1.6 is a top plan view thereof; and 1.7 is a bottom plan view thereof.

The broken lines and features of the article within the broken lines seen in Figure 1.2 form no part of the claimed design.
